PROCESS FOR PRODUCING DURENE

Robert A. Sanford, Park Forest, Ill., assignor to Sinclair Refining Company, New York, N. Y., a corporation of Maine

No Drawing. Application June 23, 1955
Serial No. 517,643

2 Claims. (Cl. 260—674)

This invention relates to a process for producing durene from hydrocarbon fractions boiling in the range from about 360° to 405° F. and having a substantial content of isomeric tetramethylbenzenes and, more particularly, to a process for obtaining increased yields of durene in which, durene is crystallized from such fractions, crystallization mother liquors are isomerized in vapor phase and additional durene is crystallized from fractions of mother liquors boiling in the range from about 360° to 405° F.

Commercially feasible durene crystallization processes generally require crystallizer feeds containing at least about 5 weight percent of durene, which feeds can be obtained by fractional distillation of petroleum reformates or aromatic alkylation products to procure relatively narrow boiling durene-containing cuts. Since a substantial portion of the durene can be separated from these fractions by a single crystallization, the durene content of crystallization mother liquors is quite low and thus repeated crystallization processing of mother liquors generally does not result in commercially significant yields of durene. However, according to the process of my invention, durene crystallization mother liquors are a source of commercially significant yields of durene, and in most instances a 75 percent increment of durene yield is obtainable.

Surprisingly, it was found that mother liquors from the crystallization of durene from polyalkylated aromatic hydrocarbon fractions, such as reformates and aromatic alkylation products, containing a substantial portion of tetramethylbenzenes and boiling in the range from about 360° to 405° F., can, under certain controlled conditions for reaction, be isomerized in vapor phase in the presence of a silica-alumina catalyst to obtain crystallizer feed fractions from which significant yields of durene can be obtained. In the isomerization step of my process, more fully described hereafter, ring isomerization of methyl groups of tetramethylbenzenes such as isodurene and prehnitene present in durene crystallization mother liquors resulting in the formation of additional durene, can be maintained the predominant reaction affecting tetramethylbenzenes, cracking and disproportionation of tetramethylbenzenes being significantly retarded. The term ring isomerization as used herein refers to shifting of intact methyl groups along and around the benzene ring of a tetramethylbenzene as distinguished from disproportionation which includes rupturing a side chain bond with relocation of the alkyl radical on a different ring. Surprisingly, it was also observed that in the isomerization step of my process, the presence in durene crystallization mother liquors of aromatic hydrocarbons other than tetramethylbenzenes, for example, C_{10} aromatic hydrocarbons such as diethylbenzene, methylhydrides and also undetermined components do not adversely affect the ring isomerization of methyl groups of tetramethylbenzenes by causing to any significant degree undesirable side reactions. Neither does it appear that components in the feed other than tetramethylbenzenes are isomerized to

2

form one or more tetramethylbenzenes, but rather that a substantial portion of these constituents undergo disproportionation to compounds having boiling points substantially removed from the boiling point of durene. Thus, it was found that fractionating isomerized mother liquors to obtain fractions boiling substantially in the range of the original feed, yields crystallizer feeds from which substantial yields of durene can be obtained.

The production of durene, according to the process of my invention, is best illustrated by reference to its preferred form in which an aromatic concentrate such as a petroleum reformate boiling in the range from about 370° to 405° F. and consisting essentially of polyalkylated aromatic hydrocarbons including from about 15 to 25 weight percent durene and a total tetramethylbenzene content of at least about 40 percent is cooled to a temperature below about -50° F. to cause precipitation of crystals composed substantially of durene. The mother liquor is separated from durene crystals by suitable means such as by filtration or centrifugation. The mother liquor is contacted in the vapor phase with a silica-alumina catalyst at about 0.1 to 20 W. H. S. V. and a temperature within about 50° F. of the temperature obtained from the formula:

$$T_m = \frac{22,600}{18.7 - \log W. H. S. V.} - 460$$

in which T_m is the temperature in degrees Fahrenheit for obtaining substantially isomerization equilibrium yields of durene at the selected weight hourly space velocity, W. H. S. V. The isomerized mother liquor is fractionated to obtain a cut boiling in the range from about 370° to 405° F. and durene is removed from this cut according to the crystallization technique previously mentioned.

The second mother liquor from the second crystallization of durene can be isomerized in vapor phase as before, and isomerized mother liquor can then be fractionated to obtain another substantially 370° to 405° F. durene-rich fraction from which durene can be crystallized. The process as described can be continued until the concentration of durene in a substantially 370° to 405° F. fraction of isomerized mother liquor is less than the concentration required for obtaining significant yields of durene on further crystallization. Of course, substantially exhausted mother liquor can be further processed by the addition of fresh feed to increase total tetramethylbenzene content, and recycled, for example, to the crystallization zone.

As was previously indicated, it was found according to the present invention, that mother liquors from durene crystallization can be isomerized in vapor phase in the presence of a silica-alumina catalyst in such a manner that ring isomerization of methyl groups of tetramethylbenzenes, resulting in the formation of durene, can be maintained in predominant reaction affecting tetramethylbenzenes. It was observed that a unique functional relationship exists between reaction temperature and feed rate or space velocity (W. H. S. V.), obtained by determining the weight of feed per weight of catalyst per hour, for it was noted that for each particular rate of feed or space velocity, a certain range of temperatures exist, within which range of temperatures ring isomerization of methyl groups is the predominant reaction affecting tetramethylbenzenes, and that at operating temperatures outside this range, either higher or lower temperatures, ring isomerization decreases rapidly. It has been determined that the relation between temperature and space velocity is expressed by the formula set forth in the preceding paragraph. Also, it was determined that ring isomerization remained the predominant reaction affecting tetramethylbenzenes if for a specific space velocity isomerization temperatures were within about 100°

F. and preferably within 50° F. either higher or lower of the temperature T_m . Isomerization space velocities of the present invention range from about 0.1 to 20 while corresponding temperatures are about from 550° to 1100° F. and the conditions are preferably equivalent in severity to about 800° to about 850° F. at 3.5 W. H. S. V.

Surprisingly, it was also observed that fractions of durene crystallization mother liquors consisting essentially of C_{10} aromatics but containing relatively minor amounts, for example, less than 2 percent, isomeric tetramethylbenzenes were subjected to the isomerization process of the present invention, the percent of tetramethylbenzenes in reaction products did not appreciably increase. Thus, it seems that under the controlled isomerization conditions of the present invention, only tetramethylbenzenes are isomerized to form other isomeric tetramethylbenzenes. It follows, therefore, that the percent of tetramethylbenzenes in the isomerization reaction products is directly proportional to their percentage in the feed stock employed. This is illustrated by the following example.

EXAMPLE I

A durene crystallization mother liquor boiling in the range from about 362° to 373° F., and consisting of about 2 percent or less by weight tetramethylbenzenes, about 5 percent methylhydrindenes, 60 percent dimethylethylbenzene and 30 percent non-aromatic and C_{11} and higher aromatic constituents, was vaporized and passed through a reactor containing a silica-alumina catalyst, composed of 90 percent silica and 10 percent alumina, at a weight hourly space velocity of 0.49 and a temperature of 698° F. The temperature T_m , for obtaining substantially isomerization equilibrium yields of isomeric tetramethylbenzenes at 0.49 W. H. S. V. is about 705° F. An analysis of reaction products revealed no substantial increase in tetramethylbenzene content.

The following examples are illustrative of the functional relation between reaction temperature and space velocity, W. H. S. V., in my process for the vapor phase isomerization of methyl groups of tetramethylbenzenes utilizing silica-alumina catalysts.

EXAMPLE II

A durene crystallization mother liquor boiling within the range from about 362° to 395° F. having an aromatic content of about 95 to 98 percent and consisting of about 30 percent tetramethylbenzenes (less than 2 percent durene), 15 percent methylhydrindenes, 30 percent dimethylethylbenzene and 20 percent non-aromatics and C_{11} and higher aromatic constituents was vaporized and passed through a reactor containing a 90 percent silica-10 percent alumina catalyst at atmospheric pressure and, at 0.45 W. H. S. V. The temperature within the reactor was about 696° F. An analysis of reaction products indicated no appreciable change in total tetramethylbenzene content over that of the feed stock; however, a substantial increase in the amount of durene present to 9.1 percent, based on total weight of feed, was observed.

EXAMPLE III

The process of Example II was carried out with a similar feed but at 0.45 W. H. S. V. and a temperature of 503° F. Reaction products analyzed 5.4 percent durene.

This significant difference in results, as indicated by durene content in the two separate reaction products of Examples II and III is attributable to the different reaction temperatures employed at substantially the same space velocity. At 0.45 W. H. S. V., the temperature T_m for obtaining substantially isomerization yields of isomeric tetramethylbenzenes is about 700° F. The substantial increase in durene content from less than 2 percent in feed to 9.1 percent in reaction products when isomerization was conducted at 0.45 W. H. S. V. and

696° F. is thus due to the fact that the process was conducted substantially under operating conditions which produce isomerization equilibrium yields of tetramethylbenzenes. On the other hand, when isomerization was conducted at 0.45 W. H. S. V. and a temperature of 503° F., about 300° F. from the temperature T_m , only a slight increase in durene content occurred.

Similarly, when the isomerization process was conducted with a 362° to 395° F. durene crystallization mother liquor similar to that of Example II at 3.7 W. H. S. V. and a temperature of 949° F., reaction products analyzed 9.2 percent durene. When the process was repeated at a temperature of 698° F. reaction products analyzed but 6.0 percent durene. Isomerization temperature T_m for 3.7 W. H. S. V. is about 840° F., which accounts for the excellent results obtained at 949° F. and the much poorer results obtained at 698° F.

Yield of durene by my process depends to a large degree on the tetramethylbenzene content of the original feed to the crystallizer. Suitable feed stocks include polyalkylated aromatic hydrocarbon fractions boiling in the range from about 360° to 405° F. and containing at least about 20 weight percent of tetramethylbenzenes including at least about 5 weight percent of durene. Because of the isomerization equilibrium that exists between tetramethylbenzene isomers, only a portion of isodurene and prehnitene are converted to durene during mother liquor isomerization, and thus crystallizer feeds having a total tetramethylbenzene content of less than about 20 percent generally do not produce isomerized mother liquor fractions having a durene content sufficient for obtaining significant yields of durene. A preferred crystallizer feed is a petroleum reformate fraction boiling in the range from 370° to 405° F. and containing about 40 weight percent tetramethylbenzenes including at least about 15 weight percent durene. Also, fractions boiling within about this range obtained from products resulting from the alkylation of aromatic hydrocarbons, as for example, those products resulting from the alkylation of xylenes with methyl chloride, are excellent crystallizer feeds.

Separation of durene from an original charge stock and isomerized mother liquor fractions is accomplished by crystallization techniques generally familiar to the petroleum industry. The temperature to which a durene-containing hydrocarbon fraction must be chilled in order to precipitate durene in a crystalline or solid state is dependent upon the concentration of durene in the particular crystallizer feed, the greater the durene content the higher the crystallization temperature which can be employed. Crystallization temperatures range from about -100° F. for crystallizer feeds containing about 5 percent durene to about -20° F. for feeds containing about 50 percent durene. Of course, crystallization temperatures exist intermediate of and above those specifically mentioned and depend upon durene concentration in crystallizer charge stock. Mother liquors are generally separated from durene crystals by centrifugation or filtration.

The crude durene cake can be purified by recrystallization either with or without the employment of solvents. In a preferred form of the invention a hydrocarbon fraction similar to the preferred crystallizer feed mentioned above containing about 15 percent durene, is chilled to a temperature below about -50° F. and durene crystals are separated from the mother liquor by centrifugation. The crude cake is melted and then cooled to about 20 to 30° F. at which temperature the newly formed cake is filtered and washed with a suitable solvent such as acetone. The successive durene separation and purification steps following isomerization of mother liquors from the preceding durene crystallization can be carried out in like manner.

As was mentioned earlier, the isomerization step of my process not only produces additional durene, but

also causes the disproportionation of a substantial portion of non-tetramethylbenzene constituents present in the durene crystallization mother liquors to compounds having boiling points substantially removed from the boiling point of durene. Thus, by fractionating isomerized mother liquors to obtain fractions boiling in the range from about 360° to 405° F., crystallized feeds can be obtained having durene concentrations greater than about 5 percent and generally having concentrations of durene from about 10 to 15 percent. Isomerized mother liquors are preferably fractionated so as to obtain a cut boiling in the range from about 370° to 405° F.

Catalysts for the present invention are of silica-alumina composition and include synthetic composite gel catalysts comprising a major portion of silica and a minor portion of alumina. Catalysts of this type are well known and widely used in the oil industry for the conversion or cracking of hydrocarbon oils. They ordinarily contain from about 50 to 95 percent of silica and from 50 to 5 percent of alumina. A preferred catalyst is one composed of 90 percent silica and 10 percent alumina. Of course, the catalyst may contain minor amounts of other materials; and catalyst diluents, such as tabular alumina, may be present in the catalyst bed so long as they do not deleteriously affect the isomerization process.

The obtaining of substantial additional yields of durene according to the process of my invention will be clearly evident from the following examples thereof, which examples are given merely by way of illustration and are not to be construed as limiting the scope of my invention. In each of the examples, all percentages are based on total weight of original feed to the first crystallization step unless otherwise indicated.

EXAMPLE IV

A substantially C_{10} aromatic concentrate boiling at about 370° to 395° F. having a total tetramethylbenzene content of about 52 percent and containing about 22 percent durene, 8 percent methylhydrindenes, 20 percent dimethylethylbenzenes, and 20 percent non-aromatic and C_{11} and higher aromatic constituents was chilled to -100° F. and a yield of 19.9 percent durene in crystalline form was obtained after separation of mother liquor by filtration. The mother liquor containing about 2.1 percent durene was vaporized and passed through a reactor containing a silica-alumina catalyst, composed of about 90 percent silica and 10 percent alumina, at substantially atmospheric pressure and at a temperature of 700° F. and 0.5 W. H. S. V. Freezing point data indicated the isomerized mother liquor to contain about 10.9 percent durene. The isomerized mother liquor was fractionated to remove constituents boiling above 404° F. and then was chilled to -100° F. A yield of 7.2 percent durene as crystals was obtained after separation of a second mother liquor by filtration. The second mother liquor was vaporized and contacted with a silica-alumina catalyst under the conditions previously described. The second isomerized mother liquor analyzing 6.9 percent durene was fractionated to obtain a cut boiling below 404° F. This cut was chilled to -100° F. and a yield of 4.2 percent durene crystals was obtained. The third mother liquor was subjected to the isomerization, fractionation and crystallization steps described above and a yield of 1.7 percent durene crystals was obtained from isomerized mother liquor analyzing 4.6 percent durene. The process was again carried out using the mother liquor from the previous durene crystallization step and a yield of 0.9 percent durene was obtained from isomerized mother liquor analyzing 5.6 percent durene based on feed to the last isomerization stage.

EXAMPLE V

A substantially C_{10} aromatic concentrate boiling at 75

about 370° to 404° F. having a total tetramethylbenzene content of about 45.2 percent and containing about 17.6 percent durene, 12.6 percent methylhydrindenes, 16.9 percent dimethylethylbenzenes, and 25.3 percent non-aromatic and C_{11} and higher aromatic constituents was chilled to -100° F. and a yield of 15.7 percent durene in crystalline form was obtained after separation of mother liquor by filtration. The mother liquor containing about 1.9 percent durene was vaporized and passed through a reactor containing a silica-alumina catalyst, composed of about 90 percent silica and 10 percent alumina, at substantially atmospheric pressure and at a temperature of 850° F. and 3.7 W. H. S. V. Freezing point data indicated the isomerized mother liquor to contain about 10.2 percent durene based on feed to this stage. The isomerized mother liquor was fractionated to obtain a substantially 370° to 404° F. cut which was chilled to -100° F. A yield of 5.4 percent durene was obtained as crystals after separation of a second mother liquor by filtration. The second mother liquor was combined with light ends and bottoms obtained from the fractionation of isomerized first mother liquor and was vaporized and contacted with a silica-alumina catalyst under the conditions previously described. The second isomerized mother liquor analyzing 8.2 percent durene based on feed to this stage was fractionated to obtain a cut boiling at about 370° to 404° F. This cut was chilled to -100° F. and a yield of 4.2 percent durene crystals was obtained. The third mother liquor was combined with light ends and bottoms as before and was subjected to the isomerization, fractionation and crystallization steps described above and a yield of 2.5 percent durene crystals was obtained from isomerized mother liquor analyzing 6.7 percent durene based on feed to this stage.

Referring to Example IV, an increment of 71 percent durene, based on weight of durene originally crystallized from a 370° to 395° F. cut, was obtained by recycling mother liquors four times to the isomerization step and separating durene from fractions of isomerized mother liquor boiling below about 404° F. In Example V, a 77 percent increment in durene yield was obtained from a 370° to 404° F. crystallizer feed stock by recycle of mother liquors three times. Table I shows the increment obtained by each recycle of mother liquor according to my process.

Table I

Number of Times Recycled	Total Percent Increment	
	370°-395° F. Feed	370°-404° F. Feed
1	36	34
2	57	61
3	65	77
4	71	

Although Example V indicates that the durene obtained with each successive recycle of mother liquor steadily decreased, the percentage of durene in the central 370°-404° F. cut remained fairly constant for three cycles as is shown by the data of Table II.

Table II

Number of Times Recycled	Durene, Wt. Percent of Product	Durene, Wt. Percent 370°-404° F. cut from Isomerized Mother Liquor	
		1	2
1	10.2	12.8	
2	8.2	13.0	
3	6.7	11.9	

From Table II, it is apparent that according to my process durene is concentrated in the 370° to 404° F. fraction

of isomerized mother liquor by disproportionation of non-tetramethylbenzene constituents to compounds boiling outside this range. Thus, crystallizer feed stocks having a substantial durene content from which commercial yields of durene can be produced are obtained according to my process.

I claim:

1. A process for producing durene which comprises chilling a hydrocarbon fraction boiling in the range from about 360° to 405° F. and consisting essentially of poly-alkylated aromatic hydrocarbons including at least about 5 weight percent of durene and having a total tetramethylbenzene content of at least about 20 weight percent to crystallize durene in said fraction, separating mother liquor from durene crystals, contacting said mother liquor in vapor phase with a silica-alumina catalyst at about 0.1 to 20 W. H. S. V. and a temperature within about 100° F. of the temperature obtained from the formula:

$$T_m = \frac{22,600}{18.7 - \log_e W. H. S. V.} - 460$$

in which T_m is the temperature in degrees F. for obtaining substantially isomerization equilibrium yields of durene at the selected W. H. S. V., fractionating the isomerized mother liquor to obtain a fraction boiling in the range from about 360° to 405° F., chilling said fraction of isomerized mother liquor to crystallize durene, and separating durene crystals from said isomerized mother liquor.

2. A process for producing durene which comprises chilling a hydrocarbon fraction boiling in the range from about 370° to 405° F. and consisting essentially of poly-alkylated aromatic hydrocarbons including at least about 15 weight percent of durene and having a total tetramethylbenzene content of at least about 40 weight percent to crystallize durene in said fraction, separating mother liquor from durene crystals; contacting said mother liquor in vapor phase with a silica-alumina catalyst at about 0.1 to 20 W. H. S. V. and a temperature within about 50° F. of the temperature obtained from the formula:

$$T_m = \frac{22,600}{18.7 - \log_e W. H. S. V.} - 460$$

in which T_m is the temperature in degrees F. for obtaining substantially isomerization equilibrium yields of durene at the selected W. H. S. V., fractionating the isomerized mother liquor to obtain a fraction boiling in the range from about 370° to 405° F., chilling said fraction of isomerized mother liquor to crystallize durene, and separating durene crystals from said isomerized mother liquor.
